UNITED STATES PATENT OFFICE

JOSEPH S. WILCOX, OF ATHOL, MASSACHUSETTS, ASSIGNOR TO THE WILCOX COMPANY,
OF ATHOL, MASSACHUSETTS, A CORPORATION OF MASSACHUSETTS

DESIGN FOR A TOILET BRUSH OR SIMILAR ARTICLE

Application filed April 30, 1932. Serial No. 43,668. Term of patent 7 years.

To all whom it may concern:

Be it known that I, JOSEPH S. WILCOX, a citizen of the United States, residing at Athol, in the county of Worcester and State of Massachusetts, have invented a new, original, and ornamental Design for Toilet Brush or Similar Article, of which the following is a specification, reference being had to the accompanying drawing, forming part thereof.

Fig. 1 is a rear elevation, and

Fig. 2 is a side elevation of a toilet brush or similar article, showing my new design.

I claim:

The ornamental design for a toilet brush or similar article as shown.

JOSEPH S. WILCOX.
